(57) **CLAIM**

The ornamental design for a food tray, as shown and described.

DESCRIPTION

FIG. 1 is a front perspective view of a food tray showing our new design;

FIG. 2 is a front elevational view thereof;

FIG. 3 is a right side elevational view thereof;

FIG. 4 is a top view thereof;

FIG. 5 is a bottom view thereof; and,

FIG. 6 is a bottom perspective view thereof.

The broken lines showing are for the purposes of illustrating the environment of the article only and form no part of the claimed design.
